VALVE-LIFTING DEVICE.

Application filed June 17, 1926. Serial No. 116,644.

This invention relates to hydraulic devices for lifting valves, and particularly to devices of this nature adapted to raise the plurality of valve springs to permit the grinding of valve seats or the removal of the poppet valves of an automobile, or other internal combustion engine. The object of the invention is to provide simple and effective means for quickly and easily lifting such valves springs for this purpose.

In ordinary practice it is customary to raise a single valve spring at a time by a lever or other mechanically operated device, in order that the pins attaching the spring to the valve stem may be removed and the valve and stem extracted for cleaning and grinding. This operation is time consuming and often difficult because of the extreme tension of the valve springs. The utilization of a device constructed in accordance with my invention overcomes these objections, since a number of springs may be raised simultaneously and with but slight manual effort.

A preferred embodiment of the invention as applied in use is illustrated in the accompanying drawings, in which:

Fig. 1 is a side elevation of the improved device in inoperative position.

Fig. 2 is a sectional view on the line 2—2 of Fig. 1.

Fig. 3 is a longitudinal section on the line 3—3 of Fig. 2; and

Fig. 4 is a detail view partly in section showing a portion of the lifting device in operated position.

The lifting device comprises essentially a metal plate having openings to receive a plurality of valve stems adapted to engage the spring seats of said valve stems a piston depending therefrom intermediate one pair of adjacent openings, a base member having a cylinder for said piston, and means communicating with the cylinder adapted to elevate the piston by hydraulic pressure, whereby the valve spring will be raised to permit the removal of the retaining pin and the extraction of the valve.

The construction of the poppet valves of an automobile of the L-head type are well understood, as represented in a conventional manner in the drawings. A valve spring chamber having a top wall 5 and a bottom wall 6 contains the elements of the valve mechanism concerning which this invention has application, and permits access to such mechanism. Valve stems 7 which pass

through openings in the upper wall 5, are surrounded by springs 8 lying between the top wall 5 and spring seats 9, said seats engaging removable pins 10 in the stems. In order to remove the valve stems to grind the valves it is necessary to raise the springs 8, so that the pins 10 may be removed.

As a means of easily and conveniently accomplishing this result, there is provided a plate 11 having spaced recesses 12 and a downwardly projecting piston 13 located between the central pair of recesses. The recesses 12 are cut from the inner longitudinal edge of the plate 11 and enough to permit the pin 10 to pass freely therethrough yet sufficiently narrow to engage the spring seats 9 when the plate is inserted beneath said seats.

Piston 13 is slidable in a vertical cylinder 14 of a base member 15 upon which the plate 11 normally rests (Fig. 2) and cylinder 14 communicates through a lateral passage 16 with an attachment member 17—member 17 is preferably provided with the customary ball valve 18 and serves as a connecting fitting for the hose 19 of a pressure gun, or other source of hydraulic pressure, as by the bayonet joint shown in Fig. 4.

The outer longitudinal edge of the plate 11 may be provided with an upstanding flange 20 adapted to contact with the spring seat 9 to limit the distance of insertion of plate 11 to the proper extent, so that the inner edge of the recesses 12 will escape pins 10 when plate 11 is elevated.

When applied for operation the base members 15 rest upon the bottom wall 6 between the central pair of valve stems, plate 11 rests upon the top surface of the base member and the valve stems 7 are disposed within the corresponding recesses 12, the vertical dimensions of the device being such that the top surface of plate 11 lies beneath the valve seats 9, a slight clearance space 21 intervening. A source of hydraulic pressure, such as a grease or oil gun, is then connected to member 17, and upon the application of such pressure oil or grease is communicated through passage 16 to cylinder 14, thus lifting piston 13 and plate 11 and depressing the valve springs against top wall 5. The pins 10 may be readily removed and the valve extracted.

If it is desired to remove the pressure, yet hold the springs in raised position, a block 23 (Fig. 4) may be inserted between plate

11 and base 15. When the valves have been replaced and the pins inserted, a slight application of pressure will permit the block 23 to be removed, and valve 18 may be released to relieve the pressure in cylinder 14 and allow the valve springs to return to normal position.

A valve lifting device constructed as above described is highly efficient in operation, 10 economical of construction and extremely durable, since the parts may be fashioned of strong and rigid metals and since there are no removable elements which are likely to wear out or become damaged in use. It 15 should be understood, however, that this invention is not to be limited to the exact construction shown, for various modifications may be included within the scope of the invention as defined in the following claims.

20 We claim:

1. A device for simultaneously compressing a plurality of valve springs comprising a lifting plate adapted to engage the under sides of a plurality of valve spring seats, said 25 plate having openings to receive the valve stems, a base member normally supporting

said plate, said base member having a chamber and said plate carrying a depending piston moveable in said chamber, and means associated with the base member to admit 30 hydraulic pressure to said chamber, thereby to elevate the plate and compress the valve springs.

2. A device for simultaneously compressing a plurality of valve springs comprising 35 a lifting plate adapted to engage the under sides of a plurality of valve spring seats, said plate having openings to receive valve stems a base member normally supporting said plate and having an upturned flange at 40 its outer edge to limit inward movement thereof, a piston depending from the plate, a cylinder in the base member receiving said piston, and means associated with the base member to admit hydraulic pressure to said 45 cylinder, thereby to elevate the plate and compress the valve springs.

In testimony whereof we affix our signatures.
